JOSEPH ARTHUR HENRY HATT, OF NEW YORK, N. Y.

PHOTOPROCESS SCREEN AND METHOD OF PREPARING SAME.

1,407,029.

Specification of Letters Patent. Patented Feb. 21, 1922.

Application filed October 14, 1920. Serial No. 417,011.

To all whom it may concern:

Be it known that I, JOSEPH ARTHUR HENRY HATT, a citizen of the United States, and resident of New York, county of New York, and State of New York, have invented 5 a certain new and useful Photoprocess Screen and Method of Preparing Same, of which the following is a specification.

The invention relates to the art of printing and more particularly to the preparation of half-tone printing plates for either black or colored printing. The object of the invention is to improve the tonal quality of half-tone reproductions without the aid of 10 hand work, requiring no special manipulations of the diaphragm of the lens during exposure, when making a negative, or any moving of the source of light when the screen is used for making half-tones by the 15 printing-through-the-screen method.

The invention is illustrated in the accompanying drawings, in which Fig. 1 illustrates one part of the screen and Fig. 2 the other element of the screen of Fig. 3, while 20 Fig. 3 represents the complete screen; Fig. 25 4 is a section on lines 4—4 of Fig. 3. All views are obviously exaggerated and greatly enlarged.

In order to prepare a screen of the present 30 invention, I first provide a number of glass plates suitably coated with a sensitized film, preferably a bichromated colloid. The coating is preferably of the type described in my Patent No. 1,317,493, of Sept. 30, 1919 35 the characteristic of which is that the sensitized film upon the glass, in so far as it is not acted upon by rays of light, shall be capable of ready removal therefrom. I next provide a regular cross-line screen of suitable mesh, i. e., a standard screen of the art 40 or a special screen, such, for example, as the one invented by me and described in my Patent No. 1,175,445 of Mar. 14, 1916. This screen is placed in front of one of the glass 45 plates sensitized as described. A plain sheet of glass will usually be required between the screen and the sensitized glass plate in order to secure the proper "screen distance," which may be defined as the distance which 50 produces a round dot on the sensitized plate through the rectangular, clear glass openings of the screen. This well known prac-

tice is shown, for example, in the illustrations accompanying my Patent No. 1,134,381 of April 6, 1915. After being placed in a suitable printing frame the plate is then exposed to an arc light. By varying the time of exposure this round dot may be made larger or smaller at will. The plate is now developed, for instance, by being immersed 60 in water (cf. my Patent No. 1,317,493), and the round dot image which remains is dyed until it is quite black or opaque. The dyeing can be satisfactorily accomplished by well known appropriate aniline dyes. The 65 result of this treatment is illustrated in Fig. 1, in which the glass plate 1 is coated with a series of spaced opaque dots 2. The space between the dots is not covered by a film but is clear glass.

This plate of Fig. 1 is then used for the purpose of making the other half of my new screen. The plate of Fig. 1 is brought into contact with a second sensitized plate similar to the one from which Fig. 1 was 70 prepared and a proper exposure made. The second plate is then developed in the same manner as the first plate was developed and it is also dyed but to a different degree. The same dye that was used in making the first 75 plate can be used in making the second plate but the second plate must be left in the bath a shorter period of time or the dye bath must be diluted or a specially prepared dye bath 80 may be used, the result accomplished being, 85 in either case, to produce a translucent field 3 interspaced with clear glass openings 4, the latter corresponding in this particular 90 method of producing the second plate to the position of the dots 2 of Fig. 1. The complete plates, of which Figs. 1 and 2 are very 95 greatly enlarged portions, will, of course, if of the same size, have the dots 2 of one of the plates located at the same relative position as are the clear glass openings 4 of 100 the other plate and there will be the same number of dots 2 on one plate as there will be openings 4 in the other. Inasmuch as in putting the two plates together there is a relative displacement of the plates to bring about an alternate and intermediate relation between the dots 2 and the apertures 4 (as shown in Fig. 3), Fig. 2 is drawn so as to represent that portion of one of the two

plates which corresponds to a corresponding portion of the other plate (i. e. the plate of Fig. 1) when both portions are taken from the same area which the two plates 5 occupy in the completed screen. The feebly opaque part 3 of Fig. 2 may be described as "translucent." The effect to be accomplished is that the translucent portions 3 shall, to a certain extent, obstruct the free 10 passage of light but shall nevertheless, when the light is intense, permit it, or a part of it, to pass through. The two plates, that is the plates of Fig. 1 and of Fig. 2, are then placed together in such a manner that 15 the clear glass 4 of Fig. 2 and the opaque dots 2 of Fig. 1 do not overlap. This may be conveniently accomplished by shifting the relative position of the two plates with respect to each other. The displacement of 20 one of the two plates will amount in actual practice to a very minute distance equivalent to the width of a line or about 1/100th of an inch for a coarse screen. After the two plates are cemented or sealed together, 25 the slight projection of the edges of the glass plates due to the shifting of one of the plates on the other, may be corrected by grinding the edge until the same is even. The result is shown illustratively in Fig. 3, 30 in which is illustrated a complete screen which consists of three portions, first a general ground of translucent film 3 and upon that ground interspersed throughout the entire surface of the screen a series of 35 clear glass openings 4 and a series of opaque dots 2.

From the foregoing description it will be readily observed that instead of proceeding as described, master negatives for 40 the production of these screens may be made by almost any photographic process. It must be observed, however, as already pointed out, that in order to make a satisfactory working screen of proper optical 45 qualities, it is essential that no film be allowed to remain over the clear glass portions of the screen and that when a photographic process is used, it must be one which will leave no such film over the clear glass portions. The film, even if transparent, seems to diffuse the light and prevents it focusing 50 properly and, consequently, acts to prevent the formation of the "hard dot" which is required. In placing the two plates 1 and 2 55 in proper juxtaposition to form the complete screen of Fig. 3, the two plates may be either placed directly together, as shown in Fig. 4, or they may be slightly spaced apart to form what is known as an "air space 60 screen", the advantages of which are set forth in my Patent No. 1,066,611 of July 8, 1913.

In order to appreciate the advantages of 65 the present invention, reference will be had to the existing state of the art. The earliest

commercial screen and the one most widely used at the present time consists of two single-line-ruled-glass plates cemented together so that the lines cross each other at right angles. These lines are ordinarily of 70 equal width with the clear glass space between the lines so that the entire screen will have a series of small rectangular clear glass openings occupying about one-quarter of the area of the screen, the remaining 75 three-quarters of the area being occupied by the opaque lines. For exact reproduction of tonal values such a screen has many defects. With considerable care such a screen can be made to reproduce the tonal 80 values of a picture with reasonable correctness between the blacks and the middle grays, when the screen is used for making a "screen negative." On the other hand, it will produce with a fair degree of accuracy 85 the tones of a picture from the middle grays up to the high-lights when used for making a printing through the screen half-tone. (A printing-through-a-screen half-tone is made by placing a continuous tone negative 90 in contact with the metal or stone plate or surface previously sensitized and then placing the screen at the proper distance above the negative and exposing the combination of screen, negative and sensitized plate to 95 the direct rays of an arc lamp or the sun). When a negative is made through such a screen it is customary to manipulate the exposures by using alternately various sizes 100 of diaphragms with the object of improving the tonal values and the resulting plate is finally re-etched by hand and frequently in addition to these special manipulations, various engraving tools are employed to cut away the excess in the lighter tones caused 105 by the defective operation of the screen on the negative.

In order to improve the quality of the tonal reproduction in the case of the printing-through-the-screen method it has been 110 found necessary, when the ordinary screen is used, to move the source of light or to move the printing frame. These operations require great care and special skill. I have myself invented two types of screens which 115 are described in patents already referred to in this specification, and while each of these screens has been a distinct improvement over the opaque cemented cross-line screen, they have nevertheless failed to enable me to produce that perfection in the reproduction of tonal values which I have now 120 been able to achieve by the use of the present invention. One characteristic of the present invention which enables me to obtain these 125 important results is that instead of employing rectangular clear glass openings round holes are used. For the mere difference between the rectangular and the round shape of the apertures, I do not, however, lay 130

claim to originality except in combination with the other features of the present invention. In my Patent No. 1,175,445 I endeavored to accomplish approximately the same object which my new screen produces but the screen of that patent, consisting as it did of series of ruled lines with clear glass spaces between each series, required the rulings to be sufficiently dense or opaque to 10 form where they crossed an altogether opaque tone. Where the ruled lines did not cross, therefore, the tonal value which resulted was not regulatable but was governed by the necessity of the situation as called 15 for at the places where the lines crossed. If the translucent lines of the screen, i. e. the rulings where they did not cross each other, were less dense or opaque for the reproduction of the various tonal values, a result 20 akin to that following the use of the new screen would have resulted but it was impossible to make a satisfactory screen of that character because of the necessity of having an opaque spot where the lines 25 crossed. The translucent lines could not be made any less opaque than they had to be in order to produce the opaque spot when superposed and crossed.

I have, therefore, in making the present 30 invention, proceeded upon the foundation of a totally different manner of making a screen than that which was adopted in connection with the patents referred to. I now use two plates, one of which (Fig. 2) consists 35 of a transparent film with small round clear glass openings interspaced therethrough, the film being dyed but nevertheless much lighter in color than the translucent portions of the screen of my prior patent above referred to. 40 The clear glass openings of this plate occupy approximately the same positions as the rectangular clear glass openings in the regular or standard screens. The second plate which I now use (Fig. 1) which is placed 45 either in contact with the first named plate or is placed in front of it with an air space between, consists of small, round, opaque dots of about the same size and number as the clear glass openings of the first named 50 plate, the remainder of said second plate being clear glass. These two plates are placed together in such a manner that the opaque dot will be located in the field of the translucent portion of the first plate (see Figs. 55 3 and 4). The result is a screen consisting of clear glass round apertures surrounded by a field of very translucent color and within that translucent field there will appear round, opaque dots. The resulting half-tones produced by the use of this new screen 60 have the same texture as those made from the regular cross-line screens, the only difference being the perfect rendering of the tonal values. The use of my new screen in 65 involves no expert manipulations or special

treatments but the tonal values will almost automatically flow from the fact that the clear glass spaces, being of the proper size and number, will permit the direct passage of light in so far as the same is desired while 70 the opaque dots prevent the passage of light to the extent desired, whereas the intermediate translucent part of the screen will, according to the intensity of the light or the length of exposure, cause just the right light 75 values to be imparted to the sensitized surface in connection with which the screen is used.

What I claim is:

1. A screen comprising a transparent 80 foundation, a coating of translucent material partially but not wholly covering the transparent foundation so as to leave clear transparent spots through said coating and a series of opaque spots located in non-interfering relation with respect to the clear transparent spots.

2. A screen comprising a transparent foundation and opaque, spaced spots thereon, a second transparent foundation coated 90 with translucent material, the translucency being interrupted by spaced, clear glass spots, the two plates being superposed and united in such a way that the opaque spots and the clear glass spots do not overlap. 95

3. A screen comprising two glass plates united together, one of said plates carrying upon the surface thereof a series of opaque dots, the remaining surface of said plate being uncoated, the second plate being coated 100 with a film of translucent material interrupted by a series of clear glass dots, the union between the plates being such that the opaque dots of one plate alternate with the clear glass dots of the other. 105

4. A screen comprising two plates of transparent material suitably united together, and located in the space between the two plates, a layer of periodically perforated translucent material and a series of 110 minute pieces of opaque material, the minute pieces of opaque material being positioned in juxtaposition to the translucent material.

5. The process of producing screens which comprises preparing a transparent plate carrying upon the surface thereof a series of dots of non-transparent or opaque material, preparing a second transparent plate coated with a lightly translucent material periodically perforated to exhibit clear glass spots, and then placing the two plates in juxtaposition so that the opaque spots of one plate alternate with the clear glass spots of the other. 115

6. The process of making screens which 125 comprises producing a series of dots upon a transparent plate coated with a sensitized film consisting of material capable of ready removal except where acted upon by light, removing the film except where the dots ap- 130

pear and opaques the latter, producing a photographic print from a plate such as first described upon a second plate carrying a sensitized film having the same characteristics as the film of the first named plate, removing from said second plate so much of the film as correspond to the dots of the first plate and dyeing the remaining portion of

the film to a light translucency, and then placing the two plates together so that the opaque spots of one will alternate with the clear dots of the other.

In testimony whereof I have hereunto set my hand.

JOSEPH ARTHUR HENRY HATT.
